UNITED STATES PATENT OFFICE.

CHRISTIAN RASMUSSEN, OF KIMBALLTON, IOWA.

GATE.

1,145,511.

Specification of Letters Patent.

Patented July 6, 1915.

Application filed July 17, 1913. Serial No. 779,591.

To all whom it may concern:

Be it known that I, CHRISTIAN RASMUSSEN, a citizen of the United States, residing at Kimballton, in the county of Audubon, State of Iowa, have invented certain new and useful Improvements in Gates; and I do hereby declare the following to be a full, clear, and exact description of the invention, such as will enable others skilled in the art to which it appertains to make and use the same.

This invention relates to gates of that general class of picket gates which are opened or closed by a vertical swinging movement of one end of the gate.

An object of the present invention is to provide a novel support for relieving the main pivot of a portion of the weight of the gate when the latter is fully open.

20 A further object is to provide a novel means for opening the gate in the nature of a gravitating weight.

A still further object is to provide a novel latch for holding the gate closed against the gravitating action of the weight.

With the above objects in view the invention consists of certain novel details of construction and combination of parts herein-after full described and claimed, it being understood that various modifications may be made in the minor details of construction within the scope of the appended claims.

In the accompanying drawing illustrating this invention:—Figure 1 is a side elevation showing the gate in full lines closed and in dotted lines opened. Fig. 2 is a cross sectional view on the line 2—2 Fig. 1 showing the gate in open position. Fig. 3 is a cross sectional view on the line 3—3 Fig. 1 showing the slot in the upper pivot link. Fig. 4 is a detail view in elevation showing the latch in full lines in initial position for locking and in dotted lines in locked position.

Referring now to the drawing in which like characters of reference designate similar parts, 10 designates a pair of gate posts between which the gate is pivoted, and 11 the gate post at the free end of the gate. The gate comprises an upper rail 12 and a lower rail 13, there being a plurality of pickets 14 pivotally connected as shown at 15 and 16 to both rails. A pivot pin 17 is passed through the lower rail and through both of the posts 10, and a pair of pivot links 18 are pivotally connected as shown at 19 to the upper rail and are connected at the

rear ends to pivot bolts 20 carried by the posts 10, there being slots 21 to receive such pivot bolts. The gate thus constructed is adapted to be swung open vertically until the rails stand upright in close proximity to each other with the pickets disposed obliquely to each other as shown in dotted lines in Fig. 1.

For supporting a portion of the weight of the gate when the latter is open, a substantially U-shaped stop member 22 is secured near the ends to the inner faces of the post 10 and receives between its legs the gate, the lowermost picket bearing at the end 70 upon the upper edge of the bight of the member whereby a portion of the weight of the gate is borne by the member. The legs of the member are bent outwardly from each other as shown at 23 to produce guides 75 which promote the easy entry of the gate in between the legs of the member.

For opening the gate, a weight 24 is connected by a cord 25 to the upper rail 12 of the gate substantially midway between the 80 ends of the rail, the cord being trained through a sheave 26 carried at the upper end of a post 27 that is secured in rear of one of the gate posts 10. Gravitation of this weight will open the gate when the 85 latch thereof is released.

In forming the latch the upper rail 12 is notched at the end as shown at 28 to receive a pin 29 that projects from the gate post 11 at the free end of the gate, and pivoted at 90 one end on the upper rail as shown at 30 is a latch 31 having a notch 32 in the lower end to engage down over said pin. There is also a spring catch 33 secured at the bottom of the post 11 to receive the free end of the 95 lower rail 13.

In closing the gate the latter is pulled down to the position shown in full lines in Fig. 4 so that the notch 28 in the upper rail registers with the pin 29. The gate is then pulled forwardly until the notch receives the pin, and the latch 31 is then rocked downwardly until its notch 32 engages over the pin from above as shown in dotted lines in Fig. 4. In this position of 105 the parts the gate is positively held closed until the above movements are reversed whereupon the weight immediately gravitates and opens the gate.

From the above description it will be seen 110 that I have provided an extremely strong and durable gate of the type described

which is formed of a few simple parts that will not easily get out of order.

What is claimed, is:—

1. In a gate construction, a pair of spaced posts, an arm pivotally secured to the outer side of each of said posts and extending outwardly therefrom, a gate pivotally mounted on the outer ends of said arms remote from their pivotal points on the posts, an additional post located in spaced relation to the first mentioned posts, one end of the said gate extending between the first mentioned posts, means on the other end of the gate to engage the second mentioned post and means to raise the gate about the pivots of the said arms on the first mentioned posts upon the disengagement of the said means from the second mentioned post.
2. In a gate construction, a pair of spaced posts, arms pivotally mounted on the opposite face thereof and extending outwardly therefrom, an additional post in spaced relation to the first mentioned post, a gate pivotally mounted on the outer ends of said arms remote from the first mentioned post and having one end extending between the same, means for raising the gate about its pivot, and means upon the outer end of the

gate to automatically engage the adjacent post upon the lowering of the gate, the said means and weight being so arranged on the gate that upon the manual disengagement of the means the gate will be automatically raised.

3. In a gate construction, a pair of spaced posts, arms pivotally mounted on the outer sides thereof, an additional post in spaced relation to the first mentioned posts, a single gate section pivotally mounted on the outer ends of said arms and extending entirely between the first mentioned posts and the last mentioned post, means for detachably securing the said gate to the last mentioned post, means for raising the gate about the pivot of the arms on the first mentioned posts, and guides secured to and extending outwardly from the first mentioned posts constructed and arranged to brace the gate during its upward movement.

In testimony whereof, I affix my signature, in the presence of two witnesses.

CHRISTIAN RASMUSSEN.
